PERCOLATOR WITH SIGNAL MEANS

Ralph Zide, Brooklyn, N. Y., assignor to Perc-Tone Aluminum Products, Inc., Brooklyn, N. Y., a corporation of New York

Application September 16, 1948, Serial No. 49,499

6 Claims. (Cl. 126—388)

1

This invention relates generally to covers and more particularly to top pieces attachable to covers of tea or coffee making apparatus, in particular of the percolator type.

It is another object of the present invention to provide means affording a very efficient and unbreakable top piece suitable for percolator covers and facilitating the incorporation of audible signal means, causing a rattling noise to draw attention to a person if the coffee is prepared in the percolator machine.

Still another object of the invention is to provide means causing a reciprocal movement of a valve-like element within said top piece to thereby abut against a wall or walls of said top and bring about audible and perceptible signals.

Still a further object of the invention is to provide means seated within or directly associated with the cover of percolator or like machines so as to signal outside said cover when boiling or rising of the water takes place within the percolator.

It is a further object of the present invention to provide means preventing the top piece from becoming loose or falling off said cover after installation of said top piece on the latter.

Yet another object of the present invention is to provide means ensuring disengagement of the top piece from said cover for cleaning and other purposes.

A still further object of the invention is to provide means facilitating the manufacture of the top piece either alone or integral with the cover from aluminum or other non-ferrous metal, which will not be affected by boiling water, said cover containing only a few parts including a valve-like element which prevents spilling or ejecting of water from within said top or cover therewithout.

With the above and other objects in view, the invention will be hereinafter more fully described and the combination and arrangement of parts will be shown in the accompanying drawings and pointed out in the claims which form part of the specification.

Reference will now be had to the drawings wherein like numerals of reference designate corresponding parts throughout the several views, in which:

Fig. 1 is a fragmentary vertical sectional view of a percolator equipped according to the invention with cover and top piece containing signal means.

Fig. 2 is a sectional view taken along line 2—2 of Fig. 1.

2

Fig. 3 is a sectional view taken along line 3—3 of Fig. 1.

Fig. 4 is a bottom plan view as seen in the direction of the arrows 4—4.

5 Fig. 5 is a sectional view of the cover of a percolator with top piece in modified form.

Fig. 6 is a fragmentary top plan view of Fig. 5.

Fig. 7 is a sectional view of the cover of a percolator with a modified top piece.

10 Fig. 8 is an elevational view of the top piece of Fig. 7.

15 Figs. 9 to 12 illustrate partly in section and partly in elevation a further modified top piece constructed to fit various dimensions of openings of covers for percolators.

Fig. 13 is a fragmentary top plan view of the securing or retaining ring employed in the invention.

20 Referring now more particularly to the drawings, there is disclosed in Fig. 1 the upper part 20 of a coffee percolator which is equipped with a cover 21 adapted to fit with its arcuate end 22 over the crimped or curled edge 23 of said part 20. Cover 21 has a downwardly inclined surface 24 and a central opening 25, the latter being defined by a narrow, preferably circular rim 26.

25 While all other parts of the percolator apparatus are made from metal, plastics, etc., the opening 25 of conventional percolator covers is fitted with a glass or similar top piece or member, which, however, often gets lost or breaks and is subject to replacement.

30 According to the present invention the top piece 30, which, in the instance shown, is made preferably from a stamped aluminum material and attached to cover 21, may be integral with said cover, if desired. Top piece 30 is somewhat dome-shaped and has the upper wall 27 and the vertical circular wall 28 with flange or reinforced rib 29 which comes to lie and abut against the surface 24 adjacent rim 26 of said cover 21. The lower end or edge of dome-shaped top piece 30 terminates into a plurality of lugs or legs 31 which are adapted in applied position of said top piece at the cover opening 25 to be bent around rim 26, whereby said top piece is firmly held in place and becomes associated with the cover 21 of the apparatus 20.

35 Fig. 1 shows lugs 31 in dotted lines before and in full lines after the lugs are applied from below and against downwardly turned cover rim 26.

40 Upper wall 27 of top piece 30 has a central bore 32 through which slidably extends a rod 33 of a valve-like element 35, which comprises a baffle 45 plate or element 34 and upper and lower abut-

ments or cymbal-shaped parts 36, 37. These cymbal parts or abutments 36, 37 are affixed to the rod 33 in any suitable manner, by soldering or screw threads and are so spaced from each other that upon reciprocal movement of rod 33 through bore or perforation 32 (as indicated by arrows A—A) parts 36 and 37 will abut against wall 27 to cause an audible, as well as visible signal, as is well understood.

At the lower end of rod 33 there is disposed a dish-shaped baffle plate or element 34, which is, in this instance, circular and has downwardly directed flange parts 38 which are separated from each other by a plurality of slots 39. The diameter of baffle plate 34 is preferably so chosen that said plate clears the inner diameter of wall 28 of top piece 30. The distance of baffle plate 34 with respect to top wall 27 is predetermined. It is further preferred to arrange plate 34 a definite distance above rising pipe 40 for conducting boiling water to the distributor or sieve plate 41 which is placed on top of basket 42 releasably held at 43 on said stem 40. This basket 42 is adapted to receive ground coffee, which is brought into contact with said boiling water by means of the distributor plate 41 in a manner well known in the art.

As soon as boiling water rises in pipe 40 and is ejected therefrom according to arrows B against the underface 44 of the dished baffle plate 34 the pressure exerted by the water forces the valve-like element 35 (baffle plate 34, rod 33 and curved or cymbal-shaped members 36, 37) first in upward direction whereby hollow plate member 38 abuts against the inner face of wall 27 (indicated in dot and dash lines); subsequently element 35 returns to its normal or lowermost position by gravity whereby hollow plate member 37 comes into contact with an upper surface portion of wall 27 and causes an audible and visible signal.

During these repeated movements and ejection of the boiling water any part of the later or ground coffee particles possibly carried by the boiling water toward the upper surface of baffle plate 34 will be diverted (by curved member 36) in sideward and downward directions and escape through slots 39 and the clearance provided between the baffle plate 34 and side wall 28 as indicated by arrow C. Thus, a reciprocal movement of element 35 is obtained whereby the aforesaid members 36, 37 alternately abut against the wall 27 and bring about a perceivable or rattling signal to draw attention of the person preparing the coffee.

Figs. 5 and 6 show an embodiment of the invention as applied to cover 21 which has the downwardly directed inner rim 26 defining a central opening 25 in which top piece 50 is inserted from below said rim 26 to abut thereagainst in fixed and assembled position. Valve-like element 35 extends through the opening 32 of the wall 27 of the top piece 50 as hereinabove explained. Top piece 50 is affixed to the upper surface 24 of the cover or lid 21 by means of a split spring ring 51 which, as shown, is nested in a circular groove 53 provided in top piece 50. The split spring ring 51 abuts also against the upper end of the rim 26 adjacent surface 24.

Figs. 7 and 8 show a further modified form of the attachment of the top piece 60 to the lid or cover 21. The valve-like element 35 is carried by the top piece 60 whereas the top piece itself is coupled with an inner tubular part 61 which abuts from below against rim 26 by means of a

flange 62. Tubular part 61 is further provided with an inwardly turned circular groove 63 which engages or comes to rest against slotted end part 64 of the top piece 60 whereby the inner tubular part 61 and top piece 60 tightly fit into each other and are thus detachably coupled to the lid or cover 21. Slots 65 in the lower end flange 64 of top piece 60 contribute to the springiness of the top piece 60, as may be easily realized.

Figs. 9 to 13 illustrate a modified detachable top piece 70 as applied to the lid or cover 21, the latter having the rim 26a providing a predetermined opening 25a in the cover 21. Dome-shaped top piece 70 terminates in a corrugated circular flange 71 which is shaped to fit various sizes of openings of lids of percolators or similar machines.

According to the sizes of the percolator covers the openings are different in diameter, such as demonstrated in Figs. 9, 10, 11 and 12 wherein the respective diameters of the openings are designated by numerals 25a, 25b, 25c and 25d.

As seen in Fig. 9 a slotted and springy retainer ring 72 having the slots 73 is employed to engage with its curve shaped end 74 the inwardly turned circular groove or recess 74a of top piece or cover extension 70 in which ring member 72 is nested in applied position and extends along the upper surface 24 of lid 21 against which ring member 72 abuts.

Flange 71 has differently spaced corrugations 75, 76, 77, 78, which are of such shape or configuration that while the position of slotted retainer ring 72 with respect to the groove 74a is substantially not altered, flange 71 comes into abutting position and tight engagement from below with any of the rims 26a, 26b, 26c, 26d, as the case may be. Various openings 25a, 25b, 25c and 25d of commercially used covers are thus taken into consideration, so that top piece or cover extension 70 may be applied to or associated with various known constructions of percolator covers having various dimensions of openings. On the left hand side of Figs. 10, 11 and 12 top piece or cover extension 70 and cover 21 are shown in section, whereas the right hand side of these figures illustrates top piece or cover extension 70 and cover 21 in side elevation.

As may be gathered from Fig. 9 baffle plate 34 is adjustably supported on rod 33, as by threaded rod portion 33a and lock nut 34a, which engages the latter. Thus the distance of the plate 34 from the upper end of stem or rising pipe 40 may be easily regulated whereby the extent of the up and down movements of valve element 35 may be predetermined.

It is further to be noted that the particular shape of member 36 prevents any escape of boiling water through bore 32 through which rod 33 extends.

It is well understood that the corrugations of flange 71 are preferably so shaped that they facilitate a tight engagement with the respective rim of the cover, whereby the escape of any boiling water and the like from within the percolator is entirely avoided.

It can thus be seen that there has been provided according to this invention a novel attachment to percolator machines, which attachment may be connected with the cover or may form an integral part with the cover and which is of sturdy construction and fulfills all requirements of the practice. The signal means contained in the hollow cover or body attached to the latter extends from the cover therewithout and is actu-

atable by the boiling water ejected in cyclic motions from the rising pipe to provide a perceivable signal without the percolator so that a person is enabled to readily check when the coffee in the percolator is being prepared.

Although the invention has been described with reference to certain specific embodiments thereof, it is to be distinctly understood that various modifications and adaptations of the arrangements herein disclosed may be made as may readily occur to persons skilled in the art without constituting a departure from the spirit and scope of the invention as defined in the objects and in the appended claims.

Having thus described the invention, what is claimed as new and desired to be secured by Letters Patent, is:

1. A percolator and like apparatus comprising a cover for said apparatus, and a valve element accommodated within said cover and including at least one dish-shaped plate member within said cover and a rod, said rod being arranged for reciprocal movement partly within said cover and partly therewithout whereby said plate member when exposed to impingement by boiling substance within said apparatus causes through said rod a perceivable signal without said apparatus, said rod including at least one abutment member positioned without said cover and smaller in size than that of said plate member.

2. A percolator and like apparatus having a cover with an inner surface and with an outer surface and having a central opening; comprising a dome-shaped top piece arranged to be seated on said cover for closing said opening, said top piece having a wall provided with a bore, a rod extending through said bore from within said top piece therewithout, a member positioned outside of said top piece and at one end of said rod to thereby bear against said wall of said top piece therewithout, a dish-shaped element connected to said rod at the opposite end thereof and within said top piece, abutment means supported by said rod and adapted to abut against said wall of said top piece therewithin, said top piece including a flange adapted for contact with the inner surface of said cover adjacent said opening, and retaining means associated with said dome-shaped top piece and extending therefrom for engagement with the outer surface of said cover whereby upon impingement of boiling substance through said opening of said cover against said dish-shaped element said rod is moved to bring about successively abutment of said member and of said abutment means against said wall of said top piece.

3. A percolator and like apparatus having a cover with an inner surface and with an outer surface and having a central opening; comprising a dome-shaped top piece shaped to be remov-

ably connected to said cover for closing said opening, said top piece having a wall provided with a bore extending in axial alignment with said cover opening, a rod extending through said bore from within said top piece therewithout, a member positioned outside of said top piece and fixed to one end of said rod to thereby bear against said wall of said top piece therewithout, a dish-shaped element connected to said rod at the opposite end thereof, abutment means supported by said rod and adapted to abut against said wall of said top piece therewithin, said top piece including means adapted for contact with the inner surface of said cover adjacent said opening thereof, and retaining means associated with said dome-shaped top piece and engaging said outer surface of said cover whereby upon impingement of boiling substance passing through said opening of said cover against said dish-shaped element said rod is moved to bring about successively abutment of said member and of said abutment means against said wall of said top piece.

4. A percolator according to claim 3, wherein said dish-shaped element is threadedly connected to the opposite end of said rod, to thereby regulate the position of said element with respect to said cover opening.

5. A percolator according to claim 3, wherein said dish-shaped element is positioned a predetermined distance from said wall of said top piece when said member bears on said wall of said top piece therewithout, said dish-shaped element being larger in size than said member.

6. A percolator according to claim 3, wherein said dish-shaped element and said dome-shaped top piece are substantially cylindrically shaped, the outer diameter of said dish-shaped element being smaller than the inner diameter of said dome-shaped top piece.

RALPH ZIDE.
